(57) **CLAIM**

We claim the ornamental design for packaging for dough product, as shown and described.

DESCRIPTION

FIG. 1 is a perspective view of a packaging for dough product showing our new design;

FIG. 2 is a top plan view thereof;

FIG. 3 is an end view thereof;

FIG. 4 is a side view thereof;

FIG. 5 is an end view of a modified form of the embodiment shown in FIG. 1;

FIG. 6 is a side view of the embodiment shown in FIG. 5;

FIG. 7 is a top plan view of the embodiment shown in FIG. 1, the extra broken line showing a package for a dough product which represents a series of objects and forms no part of the claimed design; and,

FIG. 8 is a top plan view of a modified embodiment of the design shown in FIGS. 1, 3 and 4.

The broken line showing of a representative dough product is included for the purpose of illustrating environmental structure only and forms no part of the claimed design.
